UNITED STATES PATENT OFFICE.

GEORGE E. HIBBARD, OF CHICAGO, ILLINOIS.

ACCELERATING DRY-PIPE VALVE.

1,420,192.

Specification of Letters Patent. Patented June 20, 1922.

Application filed December 16, 1920. Serial No. 431,163.

To all whom it may concern:

Be it known that I, GEORGE E. HIBBARD, citizen of the United States, residing at Chicago, in the county of Cook and State 5 of Illinois, have invented certain new and useful Improvements in Accelerating Dry-Pipe Valves, of which the following is a specification.

This invention relates to accelerating dry 10 pipe valves forming parts of fire extinguishing systems wherein sealed sprinkler heads are employed in connection with piping extending within the structures to be protected, the piping being charged with 15 air under pressure whereby a valve is held against the pressure of the city water. To this class or type of valves the present invention belongs, and has for its object the combining of parts of special construction 20 and arrangement that are believed to result in considerable economy as to original cost of manufacture, of installation and of maintenance, and by which the air valve and the main or water valve are most 25 promptly and certainly actuated when the sealing of a sprinkler head melts and the air pressure falls quickly and materially.

In the accompanying drawings the parts 30 of this invention are illustrated, and their forms and disposition shown. Fig. 1 represents a vertical sectional view through all parts assembled. Fig. 2 is a vertical section, somewhat enlarged, through a portion 35 of the diaphragm, and the movable center member, showing the restricting devices for the air-flow passing into the excess pressure chamber.

Throughout the drawings and description of the parts, the same letter is used to 40 refer to the same thing.

Considering the drawings, the valve casing A has within it an inner tube a, at the top of which is seated the main or water valve B, having a flexible edge portion b. 45 The flexible edge of the main valve rests upon the annular seat C that encircles the differential air chamber D surrounding the tube a at the top thereof. The chamber D is open to the atmosphere by way of the drain tube d, therefore, in the customary 50 way, a lesser air pressure to the unit of area above the main valve B would hold the valve seated against a greater water pressure upon it in the tube a. 55 Communicating with the differential air chamber D is a tubular elbow E, its out-

mouth being a seat for the ball valve e, termed in this explanation the air valve. Valve e has a pivot F, and an upwardly projecting trigger or finger f. These parts 60 will be again mentioned.

Within the casing suitably arranged is the valve-operating or more exactly the valve-starting weight G, which is provided with a pivot g, a recess to cover the end of 65 elbow E when the weight falls, the recess being marked H, and a smaller notch h disposed to engage the trigger f of the valve e and to "kick off" or start that valve when the weight falls. The weight G has further the projection J that engages a lug j 70 on the main valve B, and which will be referred to later hereinbelow.

The weight G is supported in its raised position by the engagement of the notch K 75 in the upper edge of the weight, and the wedge end of a slotted arm k. The arm k is pivotally attached to the lever L, and the lever is carried on hanger plate M by pivot m. As best shown in Fig. 2, the lever L is 80 pivotally connected with the bolt N, which is made with a spreading head as shown, and which serves to clamp the portions of the movable center member to the main diaphragm n, that lies against the removable head O of the casing A. The diaphragm is thus maintained against any sudden pressure towards the head O or the excess pressure chamber of which the hemisphere P is the wall or housing. The pres- 85

sure in the excess pressure chamber may be reduced, and any water drained from it by means of the valve Q, shown in Fig. 1. The bolt N, as set forth in Fig. 2 has an axial passage R extending through it. When the 90 valve casing A is filled with air at the system pressure, air enters the right-hand end r of the passage through the bolt N, and by way of the transverse passage S in the bolt it passes in front of the central check dia- 95 phragm s, then through the orifices T in diaphragm s into the chamber t. The chamber t is formed between the portions U and V of the center member, and these portions are clamped together by the bolt N at the 100 same time engaging the edges of the middle of the diaphragm n as illustrated. After passing through the central check dia- 105 phragm s the air flows by way of the transverse passage u in the bolt into the axial 110 passage R and into the excess pressure chamber enclosed by the hemisphere P de-

scribed. Air may also pass outwardly by way of the transverse passages *v* in the bolt into the radial passage *W* formed in the rear portion *V* of the center member, and there may be a plurality of such radial passages. In that way air reaches the rear of the main diaphragm *n*, and the pressure is equalized on both sides of both diaphragms. The chamber *w* extends all around the center member, and is in open communication with the passage *W* as shown. The center member, comprising the portions *U* and *V*, is in practice usually made of hard rubber.

To explain the operation of this invention, let it be assumed that the parts illustrated and explained form a part of a complete fire extinguishing system of the character stated at the beginning of this specification, and that the system air pressure exists above the main or water valve *B*. The valves are closed and the weight is releasably held in its raised position as set forth in Fig. 1. In a short time the air pressure on both front and rear sides of the diaphragms will be the same and the excess pressure chamber will become charged. Now, let it be supposed that a sprinkler head sealing is melted and its valve blown off, with a material and somewhat rapid reduction of air pressure in the valve casing *A*. The air in the excess pressure chamber cannot escape rapidly, and forces diaphragm *n* and the center member to the right, operating the lever *L* and arm *h*, and releasing the weight *G*. In falling the weight first strikes the trigger *f* of the air valve and "kicks off," in other words lifts the air valve *e*, allowing system air to enter the differential air chamber *D*, thereby further and promptly reducing the amount of pressure upon the main valve *B* which was holding the water in the inner tube *a*. The main valve *B* may now lift, and it is accelerated by the contact of the lower angle of the weight *G* with the lug *j*. The main valve *B* is now thrown off to one side as shown by broken lines in Fig. 1, and the water fills the system and is discharged by way of the uncovered sprinkler head in the usual manner.

Having now described this invention, and explained the mode of its operation, what I claim is:—

1. In a dry pipe valve, the combination with a casing of an inner tube, a main water valve seated upon the said tube, a differential air chamber surrounding the said tube at the top, an annular seat encircling the said air chamber, the said main valve having a flexible edge portion engaging the said annular seat, pivotal devices for supporting the said main valve, an air valve closing the said air chamber and having a trigger, a valve-operating weight constructed to engage and actuate said air valve and main valve, the said casing having a re-

movable head, a diaphragm located within the casing against said removable head, an excess pressure chamber carried externally by the said head, a movable center member attached to the diaphragm and extending through the said head and exposed in the excess pressure chamber, escapement devices engaging the said weight and operated by the said movable member to drop the weight, and air-flow restricting means for retarding the flow of air from the said excess pressure chamber.

2. In a dry pipe valve, the combination with a casing, of an inner tube, a main water valve seated upon the said tube, a differential air chamber surrounding the said tube at the top, an annular seat encircling the said air chamber, the said main valve having a flexible edge portion engaging the said annular seat, pivotal devices for supporting the said main valve, an air valve closing the said air chamber, a valve-operating weight constructed to engage and actuate said air valve and main valve, the said casing having a removable head, a diaphragm located within the casing against said removable head, an excess pressure chamber carried externally by the said head, a movable center member attached to the diaphragm and extending through the said head and exposed in the excess pressure chamber, escapement devices engaging the said weight and operated by the said movable member to drop the weight, and air-flow restricting means formed in and carried by the said movable member for retarding the flow of air from the said excess pressure chamber.

3. In a dry pipe valve, the combination with a casing, of an inner tube, a main water valve seated upon the inner tube, a differential air chamber surrounding the tube at the top, an annular seat encircling the said air chamber, the said main valve having a flexible edge portion engaging the said annular seat, pivotal devices for supporting the said main valve, an air valve for closing the said air chamber, a valve-operating weight and separable devices whereby the weight engages and actuates the said main valve and air valve, an excess pressure chamber carried by said casing, a diaphragm extending across the said excess pressure chamber, means extending across the excess pressure chamber, for supporting the diaphragm against pressure exerted towards the chamber, a movable center member attached to the diaphragm and exposed in said excess pressure chamber, escapement devices engaging the said weight and operated by the said movable member to drop the weight, and air-flow restricting means for retarding the flow of air from the said excess pressure chamber.

4. In a dry pipe valve, the combination

with a casing, of an inner tube, a main water valve seated upon the inner tube, a differential air chamber surrounding the tube at the top, an annular seat encircling the said air chamber, the said main valve having a flexible edge portion engaging the said annular seat, pivotal devices for supporting the said main valve, an air valve for closing the said air chamber, a valve-operating weight and separable devices whereby the weight engages and actuates the said main valve and air valve, an excess pressure chamber carried by said casing, a diaphragm extending across the said excess pressure chamber, means extending across the excess pressure chamber for supporting the diaphragm against pressure towards the chamber, a movable center member attached to the diaphragm and exposed in said excess pressure chamber, escapement devices engaging the said weight and operated by the said movable member to drop the weight, and air-flow restricting means formed in and carried by the said movable member for retarding the flow of air from the said excess pressure chamber.

5. In a dry pipe valve, the combination with a casing, of a main water valve seated within the casing, a differential air chamber surrounding the seat of the said valve, an air valve closing the said air chamber, a valve-operating weight constructed to engage and operate the said air valve, an excess pressure chamber, a diaphragm extending across the excess pressure chamber for supporting the diaphragm against pressure towards the chamber, a movable center member attached to the diaphragm and exposed in said excess pressure chamber, escapement devices engaging the said weight and operated by the said movable member to drop the weight, and air-flow restricting devices to retard the flow of air from the said excess pressure chamber.

45 6. In a dry pipe valve, the combination with a casing, of a main water valve seated within the casing, a differential air chamber

surrounding the seat of the said valve, an air valve closing the said air chamber, a valve-operating weight constructed to engage and operate the said air valve, an excess pressure chamber, a diaphragm extending across the excess pressure chamber for supporting the diaphragm against pressure towards the chamber, a movable center member attached to the diaphragm and exposed in said excess pressure chamber, escapement devices engaging the said weight and operated by the said movable member to drop the weight, and air-flow restricting devices formed in and carried by the said movable member for retarding the flow of air from the said excess pressure chamber.

7. In a dry pipe valve, the combination with a casing, of a water valve, a differential air chamber, an air valve closing said air chamber, a valve-operating weight, an excess pressure chamber, a diaphragm suitably supported across the said chamber, a movable center attached to the diaphragm, separable devices actuated by the said member for supporting and dropping the said weight, and air-flow restricting devices formed in and carried by the said member for retarding the flow of air from the said excess pressure chamber.

8. In a dry pipe valve, the combination with a diaphragm, of a center member comprising two portions, a clamping bolt passing through said portions and having an axial passage, a chamber formed between the portions of the said member, a central check diaphragm located in the said chamber and provided with openings, the said bolt having transverse passages opening in front and in rear of the diaphragm whereby air may pass into said chamber through the said diaphragm but is checked in flowing out.

In testimony whereof I affix my signature.

GEORGE E. HIBBARD.
